UNITED STATES PATENT OFFICE.

GEORGES MARESCHAL AND HENRY ASCHEL, OF PARIS, FRANCE, ASSIGNEES, BY
MESNE ASSIGNMENTS, TO EASTMAN KODAK COMPANY, OF ROCHESTER, NEW YORK.

DEVICE FOR THE AUTOMATIC OPERATION OF THE CORRECTING APPARATUS IN THE SUPERPOSITION OF IMAGES IN COLOR CINEMATOGRAPHY.

Application filed May 4, 1921. Serial No. 466,635.

To all whom it may concern:

Be it known that we, GEORGES MARESCHAL and HENRY ASCHEL, both citizens of the Republic of France, residing in Paris, France, have invented new and useful Improvements in Devices for the Automatic Operation of the Correcting Apparatus in the Superposition of Images in Color Cinematography, which is fully set forth

10 in the following specification.

This invention relates to a device for the automatic operation or maneuvering of the correcting apparatus described in United States Patent Nos. 1,223,381 and 1,233,772 and in United States patent application Serial No. 369,637 of March 29, 1920, for automatically obtaining the necessary corrections of superposition after the first matching operation has been effected, without requiring any hand manipulation of the correcting apparatus, except for the proper control.

The device is based upon the following principle:

25 A paper band traveling with a movement which is in exact cooperation with the movement of the motion picture film, is provided with perforations which are previously formed as hereinafter set forth at all required points in such manner as to permit of establishing electric contacts at the proper time which are substituted for the contacts which would have been made by a hand operation of the said correcting

30 apparatus. The location and the length of the said perforations will thus determine the moment during the travel of the film at which a correction is to be made, and likewise the duration of the said correction.

40 The following description together with the accompanying drawings show, by way of example, an embodiment of this invention.

Fig. 1 is a diagrammatic view of the device.

Fig. 2 is a diagram showing the method of preparing the paper-band.

Fig. 3 is a front elevation of a roller brush; and Fig. 4 is a side elevation of the device shown in Fig. 3.

The shaft *a* of the motor of the screen projection apparatus actuates by means of bevel or worm gearing, on the one hand a

toothed metal cylinder *b* used to draw along the paper-band in the same manner as the film is drawn in a motion picture apparatus, and on the other hand a receiving spool *c*. A spool *d* disposed on the other side of the cylinder *b* is used as the source of supply. As shown in the drawings, the device is actuated by two worm wheels *e f* secured to the shaft *a* and engaging respectively the two worm gears *g h* upon the shafts whereof are respectively mounted the cylinder *b* and the receiving spool *c*.

The metal cylinder *b* is preferably silvered in order to obtain a good electric contact, and its speed as determined by the ratio of the actuating wheels is such that the unrolled length of the perforated paper band shall be in a determined ratio to the unrolled length of the motion picture film, for instance it may be one-twentieth of the latter, this being sufficient to provide for the requisite length of the perforations whereby a reliable electric contact is afforded. The receiving spool actuated by the worm gearing *f h* is thereby given a speed which is slightly above what is necessary for taking up the whole amount of the paper band fed by the cylinder *b*, but the said spool is actuated by friction, and the latter is so regulated that only a moderate tension shall be given to the band, this being in fact the method used for the film receiving device in the screen projection apparatus.

Upon the contact cylinder *b* are caused to bear eight brushes *l* with silver contacts, each of the said brushes being connected by the wires *m* in series in the circuit of one of the eight electro-magnets of the correcting device or matching apparatus described in United States application Serial No. 369,637, filed March 29, 1920. In the said application, the electro-magnets bear the reference 18 and 19. Furthermore, the cylinder *b* is connected by the common wire *n* either with the metal framework or with the said electro-magnets.

When the paper is caused to pass between the cylinder and the said brushes, no electric contact can take place, but upon the passage of a perforation, the corresponding brush will establish the electric contact with the cylinder *b*, and the electro-magnet con-

trolled by the said brush will be caused to act during a length of time which is proportional to the length of this perforation.

Inasmuch as the screen projection apparatus as well as this automatic control device are actuated by the same motor, and likewise the correcting apparatus proper, the variations of speed will have no effect upon the matching, that is, upon the superposition of the images.

The preparation of the paper-band is carried out as follows. The brushes are mounted upon a shaft disposed parallel to the contact cylinder *b* and are adapted to pivot about the said shaft in order to substitute for the brushes the eight pointed members *p* which are mounted in the same manner upon another shaft, as indicated in Fig. 2. Each of the said pointed members is actuated by an electro-magnet *q* which is connected in shunt upon one of the electro-magnets of the matching device or correcting apparatus proper. A return spring *r* serves to raise the said pointed member when the electro-magnet ceases to act.

Under these conditions, upon unwinding a film for the first time, each correction is recorded by the pointed members *p* and the line thus drawn is proportional to the duration of the contact. It will then suffice to replace these lines by suitable perforations, and this may be carried out in various ways, for instance by simply cutting out the paper by hand or by a perforating machine provided with a 1 millimetre punch, moving the band along at the same time by $\frac{7}{10}$ millimeter steps in order to form a continuous slot. The recording operation may likewise be effected in a very simple manner and without requiring the use of a magnet recording device, by making use of a paper band impregnated with a chemical substance which gives rise to a colored mark upon the passage of the current, and upon which the brushes inscribe a red line when the corresponding electro-magnets are caused to act. The said brushes may be constituted by milled wheels of silver which roll upon the paper and make electric contact with a cylinder which is heavily silvered.

This apparatus possesses the following advantages:

1.—It affords a means for effecting displacement or lead of the operations of matching or connection whereby these operations shall be automatically carried out by the apparatus during the passage of a sub-title and in this manner the film appears in an exactly matched state immediately after the passage of the first image, this result being obtained by a forward displacement of the perforations of the paper band in such manner that the electric contacts take place during the passage of the title.

2.—While operating, means are afforded

for preparing during the rehearsal a perforated paper strip for matching purposes whereby an entirely automatic action of the correction or the superposition of the three images is obtained at each performance.

70

3.—Correction by hand may still be carried out, and this will always take the precedence over the automatic correction, by reason of the resistance of the electro-magnets of the correcting apparatus. In the event of an accidental stoppage of the device used for the automatic operation of the correcting apparatus, or of an error in one of the perforations thereof, means are afforded for correcting this error in an instantaneous manner by the use of the hand-operated matching or correcting device without requiring any uncoupling of the automatic operating device and without interfering in any way with the regulation thereof as concerns the subsequent actuating operations which it is called upon to perform. At any instant during the screen projection, it will be possible to employ the hand operation for making any necessary correction.

80

85

90

4.—The changes to be made in any motion picture outfit are but of a slight nature and can be rapidly carried out. The additional parts consist merely of a few gear wheels and toothed drums. The paper band used for matching purposes is easily prepared and is inexpensive. A given series of pictures may be modified without any complication, inasmuch as it will suffice to modify the film and the said paper band in parallel fashion.

95

100

105

To provide for the screen projection of any kind of three-color films in an indeterminate order by means of the automatic matching apparatus, it is necessary that upon the termination of each film the apparatus shall act by its proper means to restore all the actuating devices used for adjustment to a fixed and constant point, that is, that the three projection lenses or objectives shall occupy a determined position, for instance with their optical axes situated parallel to each other and in the same vertical plane.

110

This result may be obtained, at the time of preparing the paper band for matching purposes, by gluing to the end of the film after the maker's display sign, a section of film obtained by using a motion picture camera to reproduce a cross or like stationary marking point. This marked band is projected upon the screen, and the operator superposes the images of the three crosses projected by the three lenses and obtains the exact coincidence of the same, this operation being carried out by using the handle of the correcting apparatus. The required superposition is to be effected, after the removal of the matched band, by the auto-

115

120

125

130

135

matic actuating device of the correcting apparatus itself during the passage of the maker's display sign and the preliminary connecting portion.

5 The device used for the automatic control or operation of the correcting apparatus as hereinbefore described may be employed with a correcting apparatus of any suitable character other than the device described in 10 the patent application Serial No. 369,637 filed on March 29, 1920.

Having thus described the nature of our said invention and the best means we know of carrying the same into effect, we claim:

15 1. An automatic actuating and maneuvering device applicable to correcting apparatus used for the exact superposition of images in color photography, said device comprising a suitably perforated flexible 20 non-conductive band, a conductive surface under the band, means for giving to said band a movement over the conductive surface in synchronism with the movement of the film, metal contact members which are 25 caused to bear upon the said band whereby electric contacts shall be automatically produced through the perforations of the band,

said contacts closing circuits for controlling the correcting apparatus.

2. An automatic actuating and maneuvering device applicable to correcting apparatus used for the exact superposition of images in color photography, said device comprising a metal cylinder provided with teeth upon the edges, a flexible band engaging the 30 said teeth of the cylinder, a winding cylinder for said band, means for rotating said winding cylinder and the first-mentioned cylinder by the motor employed for the travel of the film in the screen projection 35 apparatus, whereby the paper band will travel in synchronism with the film, brushes connected with the circuits of the electromagnets of the correcting apparatus, and adapted to bear upon the said flexible 40 band, perforations formed in said band whereby electric contacts shall be produced between said brushes and the cylinders for energizing the corresponding 45 electromagnets of the correcting apparatus. 50

In testimony whereof we have signed this specification.

GEORGES MARESCHAL.
HENRY ASCHEL.
